Inventor

UNITED STATES PATENT OFFICE.

ROBERT B. NEWCOME, OF AMARILLO, TEXAS.

DESIGN FOR A BOWL FOR FOUNTAIN-SYRINGES.

48,159.

Specification for Design.

Patented Nov. 16, 1915.

Application filed April 9, 1915. Serial No. 20,341. Term of patent 14 years.

To all whom it may concern:

Be it known that I, ROBERT B. NEWCOME, a citizen of the United States, residing at Amarillo, in the county of Potter and State of Texas, have invented a new, original, and ornamental Design for a Bowl for Fountain-Syringes, of which the following is a specification, reference being had to the accompanying drawing, forming part thereof.

Figure 1 is a front elevation of a bowl,

showing my new design. Fig. 2 is a side elevation thereof.

I claim:

The ornamental design for a bowl for fountain syringes, as shown.

ROBERT B. NEWCOME.

Witnesses:

RECTOR P. ROBERTS,
V. L. BLAKE.
